UNITED STATES PATENT OFFICE.

CHARLES CARSTENS, OF DAVENPORT, IOWA, ASSIGNOR OF ONE-HALF TO HERMAN FLEMING, OF DAVENPORT, IOWA.

HOISTING APPARATUS.

1,041,020.

Specification of Letters Patent.

Patented Oct. 15, 1912.

Application filed December 18, 1911. Serial No. 666,330.

To all whom it may concern:

Be it known that I, CHARLES CARSTENS, a citizen of the United States, residing at Davenport, in the county of Scott and State 5 of Iowa, have invented certain new and useful Improvements in Hoisting Apparatus; and I do declare the following to be a full, clear, and exact description of the invention, such as will enable others skilled in the art 10 to which it appertains to make and use the same.

This invention relates to improvements in hoisting apparatus.

One object of the invention is to provide a 15 hoisting apparatus having an improved construction and arrangement of carrier and means for operatively connecting the same with the track bars of the hoisting frame whereby the carriage is prevented from being 20 coming disengaged from the track bars while being raised and lowered thereon.

Another object is to provide a hoisting apparatus which will be simple, strong, durable and inexpensive in construction, efficient and reliable in operation and which is 25 particularly adapted for hoisting ice into refrigerators or ice boxes.

With these and other objects in view the 30 invention consists of certain novel features of construction, and the combination and arrangement of parts as will be more fully described and claimed.

In the accompanying drawings: Figure 1 is a front view of my improved hoisting apparatus showing the carriage in a lowered 35 position; Fig. 2 is a vertical sectional view showing the carriage in a partly elevated position; Fig. 3 is a detail perspective view of the carriage; Fig. 4 is a cross sectional 40 view through the hoisting frame and the carriage on the line 4—4 of Fig. 1 showing the manner in which the latter is secured in operative engagement with the track bars of the frame.

In the embodiment of the invention, I provide a carriage supporting frame 1 comprising a pair of track bars 2 which are preferably T or angle iron shape in cross 45 section and have their upper ends curved or turned inwardly to a slight extent as shown.

The curved upper ends of the track bars are connected together by an upper cross bar 3, while the main portion of the bars 2 are connected together at intervals by a plurality 50 of cross bars 4, said bars being spaced at

suitable distances apart to permit the frame to be employed as a ladder. Two of the bars 4 near the lower ends of the frame are flattened and have bolted or otherwise secured thereto the ends of a pair of windlass supporting bars 5 to which are secured suitable bearings 6. In the bearings 6 is revolubly mounted a shaft 7 having fixed thereon between the bars 5 a cable winding drum 8. On one end of the drum 8 is fixed a ratchet gear 9 with which is engaged a pawl 10 whereby the drum is held against retrograde movement. On the outer end of the shaft 7 is formed a crank handle 11 whereby the drum is turned in the proper direction for 60 winding or unwinding a carriage hoisting cable 12.

Secured at their upper ends to the end cross bar 3 and at their lower ends to the upper cross bar 4 is a pair of pulley supporting bars 13, said bars having the same curvature as the curved upper end of the track bars 2. Revolubly mounted between the bars 13 is a cable guiding pulley 14 around which the carriage hoisting cable 12 65 passes from the carriage 15 to the drum whereby when the cable is wound on the drum the carriage will be drawn up the track bars and when the pawl 10 is disengaged from the ratchet gear 9 and the drum 70 turned in a reverse direction the carriage will be lowered.

The carriage 15 comprises a frame consisting of cross bars 16 the ends of which are bent inwardly at right angles adjacent 75 to the outer edges of the track bars 2 as shown. Revolubly mounted on bearing bolts 17 in the upper portion of the angular ends of the bars 16 are carriage supporting rollers 18 which are adapted to travel on the upper sides of the track bars 2, while on similar bearing bolts 19 in the outer portion of the angular ends of the bars 16 are revolubly mounted carriage retaining rollers 20 which engage the under sides of the upper 80 portions of the track bars and hold the carriage in operative engagement with the track while being raised and lowered by the cable 12 in the manner described.

As clearly shown in Fig. 4 the rigid projecting arms of the carriage 15 are each provided with a pair of alining guiding and holding rollers which are properly proportioned and arranged in such a manner as to 85 closely engage with the T-shaped track bars, 90

the retaining rollers 20 being considerably smaller than the carriage supporting rollers 18, the latter contacting with and covering substantially the full outer faces of the faces 5 of the tracks, with the retaining rollers against the under flat surface and one side of the rails and adjacent to the rib portion thereof.

The cross bars 16 of the carriage frame 10 are connected together by outer and central longitudinally disposed platform bars 21 the lower ends of which are bent upwardly at substantially right angles to form supporting arms 22 which are connected together at their upper ends by a cross bar 23. The upper or outer ends of the arms 22 have formed thereon inwardly extending spurs 24 which engage the ice or other object placed on the carriage and prevents the 20 same from slipping off. The cross bars 16 of the carriage frame are further braced by diagonally arranged brace bars 25 secured at their ends to the bars 16 as shown.

By constructing the hoisting apparatus as 25 herein shown and described it will be seen that the frame thereof may be employed as a ladder for climbing into the ice box or refrigerator or to any elevated position which the frame will reach. The frame may 30 be constructed of any desired length and the side bars thereof will form tracks upon which the carriage is adapted to travel when raised or lowered in the manner described, said carriage being operatively secured to 35 the tracks by the supporting and retaining rollers 18 and 20 which prevent the carriage

from becoming disengaged from the tracks irrespective of the position or inclination of the supporting frame.

From the foregoing description taken in 40 connection with the accompanying drawings, the construction and operation of the invention will be readily understood without requiring a more extended explanation.

Various changes in the form, proportion 45 and the minor details of construction may be resorted to without departing from the principle or sacrificing any of the advantages of the invention as claimed.

Having thus described my invention, what 50 I claim is:

In a hoisting apparatus comprising a supporting frame, the latter consisting of parallel T-shaped tracks rigidly connected, a carriage having rigid arms projecting therefrom, alining rollers mounted in said arms and adapted for engagement with the outer, flat face and one side of the rail with the roller carrying arms disposed in close relation to the outer edges of the tracks whereby the carriage is prevented from lateral movement and becoming released from the rails, and a raising and lowering mechanism arranged on said frame and flexibly attached to the carriage.

In testimony whereof I have hereunto set my hand in presence of two subscribing witnesses.

CHARLES CARSTENS.
